**METHOD FOR ELECTROLYTICALLY FORMING
TAPERED OR CONTOURED CAVITIES**Lynn A. Williams, Winnetka, Ill., assignor to Anocut
Engineering Company, Chicago, Ill., a corporation of
IllinoisFiled Feb. 20, 1961, Ser. No. 90,438
8 Claims. (Cl. 204—143)

This invention relates to apparatus and methods for making cavities in metal by electrolytic means, and constitutes an improvement in and an extension of the subject matter of the following copending applications of Lynn A. Williams: Serial No. 772,960, filed November 10, 1958, entitled "Electrolytic Shaping," issued into Patent No. 3,058,895, dated October 16, 1962; Serial No. 814,450, filed May 20, 1959, entitled "Electrolytic Hole Sinking," issued into Patent No. 3,002,907, dated October 3, 1961; Serial No. 844,706, filed October 6, 1959, entitled "Electrolytic Removal of Work Materials"; Serial No. 849,595, filed October 29, 1959, entitled "Electrode for Electrolytic Shaping," issued into Patent No. 3,019,178, dated January 30, 1962; Serial No. 853,194, filed November 16, 1959, entitled "Apparatus for Electrolytic Hole Sinking," issued into Patent No. 3,120,482, dated February 4, 1964; Serial No. 35,646, filed June 13, 1960, entitled "Electrode for Electrolytic Shaping," issued into Patent No. 3,123,545, dated March 3, 1964; Serial No. 35,647, filed June 13, 1960, entitled "Electrolytic Cavity Sinking Apparatus and Method," issued into Patent No. 3,196,093, dated July 20, 1965; and Serial No. 36,314, filed June 15, 1960, entitled "Electrolytic Shaping Apparatus and Method."

The principal object of this invention is to facilitate the formation of cavities having tapered or contoured side walls with a smooth and in some instances with a high finish.

Another object is to provide electrodes for the formation of such cavities.

Another object is to increase the speed of forming such cavities.

Another object is to facilitate the manufacture of suitable tool electrodes for forming such cavities.

Other objects and advantages will appear from the following description taken in conjunction with the accompanying drawings wherein:

FIG. 1 is a schematic view in elevation of the work area of apparatus used in the practice of this invention;

FIG. 2 is a frontal view showing the working tip of a wedge electrode of this invention;

FIG. 3 is a side elevation of the electrode of FIG. 2;

FIG. 4 is an end view of the electrode of FIG. 2;

FIG. 5 is a sectional view of a workpiece showing a preliminary roughing cut;

FIG. 6 is a similar view of the same workpiece shown in FIG. 5 after finishing the cut to produce tapered side walls;

FIG. 7 is a side elevation of an electrode for forming a slot as a first step in the practice of the invention;

FIG. 8 is an end view of the electrode of FIG. 7;

FIG. 9 is a side elevation of a finishing electrode;

FIG. 10 is an end view of the finishing electrode of FIG. 9;

FIG. 11 is a sectional view of a workpiece with a roughing slot formed by the electrode of FIGS. 7 and 8;

FIG. 12 is a sectional view of the same workpiece after it has been contoured by the electrode of FIGS. 9 and 10; and

FIG. 13 is a view, partly in section, of a modified arrangement wherein a solid contouring electrode is used with the electrolyte being introduced through a hole in the workpiece.

2

In some instances, it is desired to produce cavities in which the side walls are not straight but, rather, are tapered or contoured, and it is desirable that these should be produced with accuracy at high speed, and that they should have a high degree of polish or smooth finish. While it is possible to produce contours in workpieces by the methods shown in the above identified copending applications and the patents issued thereon, it is difficult to produce good accuracy and smooth finish when the surface to be formed deviates more than about 45 to 60 degrees from a plane normal to the direction of advance of the electrode, and this invention is concerned primarily, though not exclusively, with this kind of situation. But, as will be seen, the invention may also be used to produce very smooth surfaces which are substantially normal to the path of advance of the electrode. This is shown, for example, in the electrode of FIGS. 9 and 10 and in the workpiece of FIG. 12.

In the above identified copending application patents 20 the discovery was shown that by maintaining the electrolyte under high pressure and, at the same time, maintaining high electrolyte velocity in the work gap a high surface finish could be induced in the work material, and this basic discovery is used in this invention. (See FIG. 25 24 and the related descriptive matter of the above identified copending application Serial No. 772,960, now Patent No. 3,058,895.) In that application and patent, there was disclosed the production of a high finish by the confinement of the electrolyte by use of an external 30 restriction made of neoprene or rubber sealing rings. In the instant invention the sealing, in effect, is accomplished by the electrode itself, as will more fully appear in the following description.

Briefly, it has been found that if the electrode is arranged in such a way as to cause always a kind of outwardly wedging action against the work material, thereby tending constantly to confine the electrolyte, to maintain its pressure, and to maintain high velocity, then it is possible to secure close conformation of shape between the cavity in the workpiece and that on the electrode. And, at the same time, it is possible to produce a bright, specular finish even though the electrolyte solutions used are not of the kind ordinarily regarded as having electro-polishing characteristics.

Referring to the drawings, FIG. 1 shows schematically the general configuration of the apparatus. An electrode E is mounted to a manifold M, which is fed with a hose H with electrolyte under a pressure of 100 to 300 p.s.i. at the manifold and at the entrance to the electrode. The 50 manifold M is mounted in turn to a holder H1 which is fastened to a front plate a ram R. The front plate is electrically insulated from the body of the ram, and the ram itself is protected against electrolyte by a collapsible boot B. Direct current of a voltage not appreciably 55 greater than about 18 volts is supplied from a source of the type disclosed in the copending application of Lynn A. Williams, Serial No. 863,246, filed December 31, 1959, entitled "Control and Operating System for Electrolytic Hole Sinking," by two cables C— and C+, indicating the polarity arranged to make the work an anode. The 60 machine is fitted with a worktable WT on which may be mounted a fixture F, and to this the work WK is fastened with a clamp or vise. The entire work area is surrounded by an enclosure, which is intended to prevent the undesirable exit of splatter and spray. However, the work enclosure should be provided with vents and exhausted by a power blower to prevent the accumulation of hydrogen or unpleasant or noxious gases. It should be understood 65 that the ram is arranged to be advanced under a positive drive at a predetermined fixed rate in the direction of the arrow toward the work, thereby moving the electrode linearly into the workpiece. A more detailed description

of the type of apparatus which may be used is shown in the copending application of Lynn A. Williams entitled "Electrolytic Cavity Sinking Apparatus and Method," Serial No. 73,154, filed September 2, 1960.

FIG. 2 shows one form of electrode used in the practice of the invention. It consists of an electrode proper 21, which is made of copper and is mounted in the manifold member M, which, in turn, may be either fastened to or made integrally with a holder plate H1. The manifold M is recessed as shown at 23, and provision is made for connection of a hose through a screw-threaded opening 25. The electrode 21 conforms to the shape of the recess 23 in the manifold, and may be fastened into it by any suitable means, for example, by brazing or soldering.

The electrode proper 21 is arranged to feed electrolyte from the recess 23 of the manifold to its working tip by a plurality of feed holes or passages 27. These should be drilled as conveniently close together as is possible without breaking out from one hole through the land into the next. In an electrode having a working tip with a width of the order of $\frac{1}{4}$ ", the holes should be about $\frac{1}{8}$ " in diameter, and, in general, the more open and free the passage for electrolyte the better. The holes 27 are not carried through all the way to the working tip of the electrode but terminate about $\frac{1}{8}$ " to $\frac{1}{4}$ " above it, where they are intersected by a transverse slot 29 which is milled into the end of the electrode in such a way as to communicate with the holes 27. The slot may be about $\frac{1}{16}$ " wide for an electrode of this size. The slot 29 should be deep enough so as to smooth out the flow from the several holes 27, so that the electrolyte issues smoothly through the slot with a minimum reflection of the pattern of holes through which it previously passed.

This electrode is not insulated either on its sides or on its ends, but is left bare for the purpose of producing tapered side walls 30. The electrode may be used in either of two ways. Either it may be simply advanced into a raw piece of work, using the maximum penetration rate which is obtainable, or, preferably, it may be used to enlarge a cavity previously made by a slotting electrode; for example, one like that shown in FIGS. 7 and 8 or as shown in one or more of the previously identified copending application. A cut of this preliminary kind is shown in FIG. 5. There is no basic reason why it could not be produced by conventional machining as well as by electrolytic means, although ordinarily formation of cavities of this sort can be accomplished more quickly by use of electrolytic machining techniques than by conventional methods. The width and length of the preliminary cut as shown in FIG. 5 should be about the size of the working tip of the tapered electrode shown in FIGS. 2, 3 and 4.

The method of advancing the tapered electrode directly into a workpiece without making a preliminary cut can be carried out where the taper on the sides and ends of the electrode is sufficiently great (say, 30° from the line of advance of the electrode). As the angle of taper becomes less, a point is reached where it is necessary to make a preliminary cut like that shown in the workpiece of FIG. 5. This is for the reason that it is not possible to maintain a sufficiently fast rate of frontal advance into the work to keep the tapered sides sufficiently close to the work material, which, of course, is being electrolytically removed in a generally sideward direction. By making the preliminary cut as shown in FIG. 5 it becomes possible to advance the electrode at a rate which is high enough to keep up with the rate of sideward removal, as there is no concern with the frontal removal at the tip of the electrode. In addition, the cavity shown in FIG. 5 aids in spreading the electrolyte uniformly over the entire side surfaces, for the cavity forms a kind of plenum which quickly fills with electrolyte and, thereafter, induces a uniform flow which is helpful in producing accurate work. FIG. 6 shows the

shape of the tapered cavity formed in the same workpiece shown in FIG. 5 by using the electrode of FIGS. 2, 3 and 4.

It is important that a very copious supply of electrolyte be provided, and, accordingly, the supply hose H should be large enough to deliver the full volume without substantial loss of pressure, and, similarly, the manifold recess 23 should be adequate in size to assure full flow and uniform distribution.

Referring to FIGS. 7, 8, 9 and 10, a somewhat different application of the same invention is shown. FIGS. 7 and 8 show a simple electrode for making a rectangular cavity. The electrode proper 21 may be made like other electrodes of copper. It is fitted into a recess 23 in a manifold M which, in turn, is fastened to a holder or mounting plate H1. The cavity 23 is fed by an opening adapted to receive a hose connection as at 25. The electrode proper is drilled with feed holes or passages 27, which are closely spaced as previously described in connection with the electrode of FIGS. 2, 3 and 4. A slot 29 is milled into the electrode near its tip, and, then, an additional member serving as a flange plate 31 is fastened to the body of the electrode by brazing or soldering. This additional flange plate is arranged to project beyond the body of the electrode by about $.010$ " to $.030$ " with the purpose of providing clearance for insulating material 33, which is applied to the body of the electrode to prevent excessive side action.

After this electrode of FIGS. 7 and 8 has been used to form a cavity like that shown in section in FIG. 11, then the electrode of FIGS. 9 and 10 is used in order to modify the shape of the cavity to provide radii on all of the side walls. This electrode of FIGS. 9 and 10 is made in substantially the same way as the electrodes previously described herein with like reference indicia referring to similar parts. Here, however, it is not necessary to provide any slot, but, instead, quite large feed holes 27 are used, and these pass directly through the body of the electrode 21 to feed electrolyte into the work area.

Unlike the preceding electrodes, this type is machined to a shape to provide a full radius as shown at R. This, of course, may be any contour which is desired and may be either straight or curved as the work requirements dictate.

After forming the cavity of FIG. 11, then the electrode of FIGS. 9 and 10 is positioned so that the working tip of this electrode registers with the previously formed cavity. It is not critical that the working face should have identically the same contour as the cavity, but the deviation should not be excessive and, particularly important, there should not be any place where the cavity is so much larger than the finishing electrode that any large amount of the electrolyte will escape through the gap which would thus be formed. Except for this, however, close conformity is desirable but not necessary.

After positioning the electrode of FIGS. 9 and 10 with respect to the pre-existing cavity, it is then advanced at a fairly rapid rate into the work until it has reached a depth where its working tip is close to the bottom of the previously formed cavity. If this is done rapidly, the result will be to form an accurate contour and to induce a very high finish on the work material.

In practice, an electrode like that of FIGS. 7 and 8 has been made as a roughing electrode, its dimensions being 2" in length and $\frac{3}{8}$ " in width. The cavity like that shown in FIG. 11 was produced with an infeed rate of advance of $.100$ " per minute using a direct current of 14 volts and an electrode pressure of about 200 p.s.i. The cavity in the workpiece was carried to a depth of $.200$ ".

Subsequently, an electrode like that of FIGS. 9 and 10 was applied, using a feed rate of $.200$ " per minute, an electrolyzing current at a voltage of 13 volts and a total penetration to a depth of $.187$ ".

The electrolyte used was that described in the above mentioned copending application, Serial No. 772,960.

Another electrolyte can be made of four pounds of salts to each gallon of water, the salts being in the following ratio:

Parts	
Potassium chloride	3
Potassium nitrate	1
Rochelle salts	1
Potassium citrate	1
	10

For some kinds of work a solution of about ten percent of sodium chloride can be used satisfactorily. This is particularly applicable for ordinary tool steels as distinguished from the higher nickel alloys found in stainless steel and high temperature super-alloy materials. For the latter the electrolyte of the preceding paragraph is preferred.

In FIG. 13 there is illustrated an arrangement for forming a tapered or contoured cavity without using a hollow electrode. The workpiece WK is initially formed with a through cavity 35 by electrolytic or conventional machining techniques. The workpiece is mounted or clamped in a fixture or bracket 37 having one or more passages 39 therethrough adapted to be placed in communication with the workpiece cavity 35. If the workpiece cavity is large or elongate then two, three or more fixture passages 39 fed from a manifold similar in function to the manifold M of FIGS. 2 to 4, 9 and 10, should be provided. The passage or passages 39 (or manifold if one is used) is connected to the previously mentioned electrolyte supply source by the hose H and fitting 41 so that a copious supply of electrolyte under pressure may be obtained.

The electrode 43 is similar in configuration (for illustration purposes only) to that shown in FIGS. 9 and 10 but is made of a solid block of copper or other suitable material and is mounted directly upon the holder H1 to be connected into the electrolyzing power circuit in a manner to be cathodic. It is formed with contouring radii R' which are adapted electrolytically to form contoured surfaces R'' on the workpiece WK.

With the electric current turned on and electrolyte being supplied to the rough workpiece cavity 35, the electrode 43 is advanced into the work with a positive feed and at a constant rate. The rough cavity in the workpiece forms a plenum ahead of the advancing workpiece and as the electrolyte escapes from the cavity between the electrode surfaces R' and the workpiece the latter is electrolytically eroded to the shape of the surfaces R'' to have a smooth finish and, depending upon the character of the workpiece material, perhaps a high specular finish.

It should be appreciated that the essential difference between the first two forms of the invention and the last is the direction of electrolyte flow. In all three there is formed in the workpiece a kind of plenum to which the electrolyte is fed under high pressure and from which it escapes at high velocity between the active faces of the electrode and those portions of the workpiece being electrolytically eroded.

It has been found practical, for example, to use this method in making hollow bolts each having a recessed hexagonal socket, like an Allen screw. This can be done by electrolytically sinking a hole through the length of the bolt. Electrolyte is then introduced into the bottom of the hole and a hexagonally shaped electrode is fed into the head of the bolt cavity to enlarge it and to change its shape from round to hexagonal.

While three rather simple forms of the invention have been illustrated and described, it should be understood that many variations and complications are possible. Thus, for example, while a wedge shaped electrode is shown in FIGS. 2, 3 and 4 having a rather regular shape, other electrodes have also been used in which, while the same general tapered configuration was employed, the actual shape was the rather complex shape existing between

two blades of a turbine wheel, the blades themselves having a twist or camber and, at the same time, a constantly changing section. In this instance, a preliminary, straight-sided cut was made into a disc of material at a point roughly representing the midpoint between two of the blades. Subsequently the wedge shaped electrode formed to produce the interblade cavity was introduced at a high rate of feed in order to shape and finish the convex side of one blade and, concurrently, the adjoining concave side of the next blade.

The essential idea is that the electrode should be one in which its section grows larger as it is advanced into the work so as to remove material by side action while at all times forcing the electrode into the cavity to maintain close spacing between the electrode and the work, a spacing of the order of .015" or less while, at the same time, maintaining electrolyte pressure of the order of 100 p.s.i. or more and, at the same time, maintaining high velocity of electrolyte flow. The rate of advance necessary to bring about these conditions will, of course, be determined by the taper. If the taper is shallow, then the electrode may have to be advanced very rapidly, as rapidly, for example, as an inch per minute or even more. On the other hand, if the taper is steeper then a slower rate of advance will maintain the desired condition. In the case of the electrode shown in FIGS. 9 and 10, it has been found in practice that it is not necessary to change the rate of advance even though the rate of taper changes. Apparently, the feed rate of .200" per minute is a reasonable comprise between the rate one might use for the very slight degree of taper at the tip itself and the much greater taper approaching, in fact, a surface normal to the line of advance at the upper limit of the radius portion. Theoretically, it might be desirable to advance an electrode of this kind at first more rapidly and then more slowly, but, as has been said, it was not found to be necessary in fact in this particular instance.

Many other variations and changes may be made without departing from the spirit and scope of the invention, and the scope of the invention is to be determined from the scope of the following claims.

What is claimed as new and desired to be secured by United States Letters Patent is:

1. In the method of forming cavities having shaped side walls and the like in a workpiece capable of being electrochemically eroded wherein the cavity mouth is of appreciably greater dimensions than the base, comprising forming a preliminary generally straight sided cavity in the workpiece having transverse shape and dimensions corresponding to but not greater than those of the base of the finished cavity, advancing a finishing electrode into the cavity a relatively high feed rate of at least about .100 inch per minute, the electrode having electrically conductive shaping side walls and electrolyte passages therethrough, impressing a direct current having a voltage not greater than about 18 volts between the workpiece and the electrode in a sense to make the workpiece anodic, feeding electrolyte through the electrode passages under a pressure of at least about 100 p.s.i. at the entry to the electrode and with a high electrolyte velocity so as to fill the workpiece cavity beyond the working tip of the electrode and to escape from the cavity between the cavity walls and the electrode side walls, and maintaining a gap spacing between the electrode side walls and the cavity walls of not greater than about .015 inch, whereby the cavity walls are electrolytically eroded to a shape complementary to that of the electrode and given a smooth finish.

2. In the method of forming cavities having shaped side walls and the like in a workpiece capable of being electrochemically eroded wherein the cavity mouth is of appreciably greater dimensions than the base, comprising forming a preliminary generally straight sided cavity in the workpiece having transverse shape and dimensions corresponding to but not greater than those of the base

of the finished cavity, advancing a hollow finishing electrode into the cavity at a relatively high feed rate of at least about .100 inch per minute while impressing a direct current having a voltage not greater than about 18 volts between the workpiece and the electrode in a sense to make the workpiece anodic, the electrode having electrically conductive shaping side walls, feeding electrolyte through the electrode under a pressure of at least about 100 p.s.i. at the entry to the electrode and with a high electrolyte velocity so as to fill the workpiece cavity beyond the forward end of the electrode so as to make the workpiece cavity a plenum chamber from which the electrolyte escapes between the electrode side walls and the cavity side walls, and maintaining a gap spacing between the electrode side walls and the cavity side walls of not greater than about .015 inch.

3. In the method of forming cavities having shaped side walls and the like in a workpiece capable of being electrochemically eroded wherein the cavity mouth is of appreciably greater dimensions than the base, comprising forming a preliminary generally straight sided cavity in the workpiece having transverse shape and dimensions corresponding to but not greater than those of the base of the finished cavity, advancing a finishing electrode into the cavity of a feed rate of about .200 inch per minute while impressing a direct current having a voltage of not greater than about 18 volts between the workpiece and the electrode in a sense to make the workpiece anodic, the electrode having electrically conductive shaping side walls, feeding electrolyte under a pressure of at least about 100 p.s.i. at the entry into the cavity and with a high electrolyte velocity so as to fill the workpiece cavity beyond the forward end of the electrode so as to make the workpiece cavity a plenum chamber from which electrolyte escapes between the electrode side walls and the cavity side walls, and maintaining a gap spacing of not greater than about .015 inch between the electrode side walls and the cavity side walls.

4. In the method of forming cavities having shaped side walls and the like in a workpiece capable of being electrochemically eroded wherein the cavity mouth is of appreciably greater dimensions than the base, comprising forming a preliminary generally straight sided cavity in a workpiece having transverse shape and dimensions corresponding to but not greater than those of the base of the finished cavity, providing a hollow finishing electrode having a cross section of increasing dimensions away from its forward end and having electrically conductive shaping side walls, impressing a direct current having a voltage of not greater than about 18 volts between the workpiece and the electrode in a sense to make the workpiece anodic, feeding electrolyte through the electrode under a pressure of at least about 100 p.s.i. at the entry to the electrode and with a high electrolyte velocity so as to fill the workpiece cavity beyond the forward end of the electrode so as to make the workpiece cavity a plenum chamber, and advancing the electrode into the workpiece at a rate not greater than about one inch per minute and such that with the electrolyte outflow from the cavity between the cavity side walls and the electrode side walls a very small spacing distance of not greater than about .015 inch will be provided therebetween as the cavity is enlarged to the desired finished shape.

5. In the method of forming cavities having shaped side walls and the like in a workpiece capable of being electrochemically eroded wherein the cavity mouth is of appreciably greater dimensions than the base, comprising forming a preliminary generally straight sided cavity in the workpiece having transverse shape and dimensions corresponding to but not greater than those of the base of the finished cavity, providing a finishing electrode having a cross section of increasing dimensions away from its forward end and having electrically con-

ductive shaping side walls, impressing a direct current having a voltage of not greater than about 18 volts between the workpiece and the electrode in a sense to make the workpiece anodic, feeding electrolyte under a pressure of at least about 100 p.s.i. at the entry to the cavity and with a high electrolyte velocity so as to fill the workpiece cavity beyond the forward end of the electrode so as to make the workpiece cavity a plenum chamber, and advancing the electrode into the workpiece at a rate in the range between about .100 and one inch per minute such that with the electrolyte outflow from the cavity between the cavity side walls and the electrode side walls a spacing distance of not more than about .015 inch will be provided therebetween as the cavity is enlarged to the desired finished shape.

6. In the method of forming cavities having shaped side walls and the like in a workpiece capable of being electrochemically eroded wherein the cavity mouth is of appreciably greater dimensions than the base, comprising forming a preliminary generally straight sided cavity in the workpiece having transverse shape and dimensions corresponding to but not greater than those of the base of the finished cavity, advancing a finishing electrode into the cavity at a feed rate of about .200 inch per minute while impressing a direct current having a voltage of not greater than about 18 volts between the workpiece and the electrode in a sense to make the workpiece anodic, the electrode having electrically conductive shaping side walls, feeding electrolyte under a pressure of at least 100 pounds per square inch at the entry to the cavity and with a high electrolyte velocity to the workpiece cavity beyond the forward end of the electrode so as to fill the cavity and so that electrolyte escapes from the cavity between the cavity walls and the electrode side walls with a high velocity whereby the cavity walls are electrolytically eroded to the desired shape and given a smooth finish, and maintaining a gap spacing of not greater than about .015 inch between the electrode side walls and the cavity walls.

7. In the method of forming cavities having shaped side walls and the like in a workpiece capable of being electrolytically eroded wherein the cavity mouth is of appreciably greater dimensions than the base, comprising forming a preliminary generally straight sided cavity in a workpiece having a transverse shape and dimensions corresponding to but not greater than those of the base of the finished cavity, advancing a finishing electrode into the cavity at a relatively high feed rate of not less than about 100 inch per minute, the electrode having electrically conductive cavity shaping side walls, the feed rate being such as to maintain a gap spacing of not more than about .015 inch between the electrode side walls and the cavity side walls, impressing a direct current having a voltage of not greater than about 18 volts between the workpiece and the electrode in a sense to make the workpiece anodic, and feeding electrolyte into the cavity ahead of the advancing electrode under a pressure of at least 100 p.s.i. at the entry to the cavity so as to fill the workpiece cavity beyond the forward end of the electrode thereby to make the workpiece cavity a plenum chamber, whereby the electrolyte outflow from the cavity between the cavity side walls and the electrode side walls will be at a high velocity through the very small spacing distance between the electrode and the cavity side walls as the cavity is enlarged to the desired finished shape.

8. In the method of forming cavities having shaped side walls and the like in a workpiece capable of being electrolytically eroded wherein the cavity mouth is of appreciably greater dimensions than the base, comprising forming a preliminary generally straight sided cavity in a workpiece having a transverse shape and dimensions corresponding to but not greater than those of the base of the finished cavity, advancing a finishing electrode into the cavity at a relatively and substantially constant

rate of not greater than about one inch per minute, the electrode having electrically conductive cavity shaping side walls, the feed rate being such as to maintain a gap spacing of not greater than about .015 inch between the electrode side walls and the cavity side walls, impressing 5 a direct current having a voltage of not greater than about 18 volts between the workpiece and the electrode in a sense to make the workpiece anodic, feeding electrolyte into the cavity ahead of the advancing electrode under a pressure in excess of 100 pounds per square inch at 10 the entry to the cavity so as to fill the workpiece cavity beyond the forward end of the electrode thereby to make the workpiece cavity a plenum chamber, whereby the electrolyte outflow from the cavity between the cavity side walls and the electrode side walls will be at a high 15 velocity through the very small spacing distance between the electrode and the cavity side walls as the cavity is enlarged to the desired finished shape.
